UNITED STATES PATENT OFFICE.

THOMAS STEWART, OF PHILADELPHIA, PENNSYLVANIA.

LOCOMOTIVE-TENDER.

1,157,445.

Specification of Letters Patent. Patented Oct. 19, 1915.

Application filed February 5, 1915. Serial No. 6,249.

To all whom it may concern:

Be it known that I, THOMAS STEWART, a citizen of the United States, residing at Philadelphia, in the county of Philadelphia and State of Pennsylvania, have invented 5 new and useful Improvements in Locomotive-Tenders, of which the following is a specification.

My invention relates to new and useful 10 improvements in locomotive tenders, and has for its object to provide an exceedingly simple and effective device of this character which will prevent the shifting of the entire body of water carried in the tank of 15 the tender, thus reducing to a minimum the possibility of accidents due to this cause.

A further object of the invention is to 20 construct the water tank of a locomotive tender of a number of horizontal superimposed compartments whereby the water in the uppermost compartment only will be able to move about, and the amount of 25 water in each compartment will be practically insufficient to cause any accident by such shifting of the water.

A still further object of the invention is 30 to arrange a number of spaced parallel horizontal partitions within the tank of a locomotive tender in order to form a plurality of compartments, each of which is in communication with the adjacent compartments, through the openings in said partitions, certain of said openings having automatic or 35 float valves adjacent thereto for closing the same.

With these ends in view, this invention 40 consists in the details of construction and combination of elements hereinafter set forth and then specifically designated by the claims.

In order that those skilled in the art to which this invention appertains, may understand how to make and use the same, I will describe its construction in detail, referring 45 by numeral to the accompanying drawing forming a part of this specification, in which—

Figure 1, is a vertical sectional longitudinal view of a tender embodying my invention, showing the same coupled to a locomotive; and Fig. 2, is a section at the line 2—2 of Fig. 1, looking in the direction of the arrow.

In carrying out my invention as here embodied 50 2 represents a locomotive having a tender 3 coupled thereto.

The tender 3 is divided into a coal bin 4, and a water tank 5 of any desirable size, shape and construction, and provided with the ordinary means for filling the same as 60 the inlet 6 normally closed by the cap 7 or the scoop 8 adapted to receive water from the trough 9, from which point the water is conveyed to the top of the tank by means of the intake pipe 10.

The water tank 5 is sub-divided by means of suitable parallel partitions 11 into a number of horizontal super-imposed water compartments 12, each of which is in communication with the adjacent compartments 70 through the inlet openings 13, and the vent openings 14 formed in the partitions.

The inlet openings 13 to each of the compartments are closed by suitable valves 15 which will float upward as the compartments are filled, and automatically close the 75 openings 13, the valves here shown being as the ordinary hinged flapper valve of leather or other suitable material, their downward or opening movement being limited by suitable brackets or stops 16.

The water is drawn off from the bottom of the water tank, and delivered to the locomotive boiler by means of the ordinary outlet pipe 17.

In practice the water tank of the locomotive tender is filled at the top in the ordinary manner, the water first entering the uppermost compartment and flowing through the different inlet openings 13 90 through the different compartments into the lowermost one, and as said lowermost compartment is full, the valve controlling the inlet opening thereto will float upward and close the inlet opening, and in like manner 95 each of the compartments will be filled until the entire tank is full. The water is drawn off from the water tank in the ordinary manner and fed to the locomotive boiler, and as the outlet pipe leads from the 100 lowermost water compartment, the water from said compartment will be kept at its ordinary level by the supply from the succeeding superimposed compartments. As the tender travels over the track the same 105 receives a swaying motion from a number of different well known causes, which in the case of the ordinary tender causes the water to be splashed about and shifted considerably, which has a tendency to overturn the 110 tender, thereby causing accidents with great loss of life and property, but by the use of

my improvement the water in the filled compartments will be unable to splash about and the amount of water in any of the unfilled compartments being so small relatively 5 that the shifting thereof will not cause the tender to capsize. The inlet openings 13 being closed by the valves 15 when the compartments are filled, will prevent the water from one of the filled compartments from 10 entering the unfilled compartment during the swaying of the tender, and should any of the valves for any reason stick and not open the water will drain therefrom through the vent openings 14.

15 Of course I do not wish to be limited to the exact details of construction as here shown, as these may be limited to the exact details of construction as here shown, without departing from the spirit of my invention. 20

Having thus fully described my invention, what I claim as new and useful, is—

1. A locomotive tender provided with a water tank, a plurality of partitions therein 25 for sub-dividing the same into a number of superimposed compartments, said partitions having openings therein, certain of which are valve controlled.

2. A locomotive tender provided with a 30 water tank, a plurality of partitions therein for sub-dividing the same into a number of

superimposed compartments, said partitions having openings therein, and valves for controlling certain of said openings.

3. A locomotive tender provided with a 35 water tank, a plurality of partitions therein for sub-dividing the same into a number of superimposed compartments, said partitions having openings therein, valves for controlling certain of said openings, and means 40 for limiting the opening movement of said valves.

4. A locomotive tender provided with a water tank, a plurality of spaced horizontal partitions extending the entire length and 45 width of the tank for dividing the interior thereof into a plurality of relatively low compartments extending the entire length of the water tank, each of said partitions having two different size holes therein, the smaller hole designed principally for the outlet of air, a valve hinged to the underside of each of the partitions for controlling the larger openings, and means for limiting the opening movement of said valves. 50

In testimony whereof, I have hereunto affixed my signature in the presence of two subscribing witnesses.

THOMAS STEWART.
